ADJUSTABLE STRETCHER

William H. Jacobus, New York, N. Y.

Application March 7, 1936, Serial No. 67,564

2 Claims. (Cl. 223—69)

This invention relates to adjustable stretchers and more specifically to an adjustable frame on which garments or other articles are stretched. However, it is to be distinctly understood that the 5 invention is not limited to a stretcher for any particular garment, but for convenience and to prevent constant repetition we will assume that the stretcher is designed for stretching skirts.

An object of the invention is to provide a 10 stretcher of this character which can not only be adjusted to various sizes and angles but is also provided with means whereby the outline of the stretcher can be given any desired shape, as, for example, it is a well-known fact that some skirts 15 are made and designed for larger hips than others and for various human shapes, and with my improved stretcher means are provided which permit the stretcher to assume the desired shape or outline.

With this and other objects in view, the invention 20 consists in certain novel features of construction and combinations and arrangements of parts, all of which will be more fully hereinafter described and pointed out in the claims.

In the accompanying drawing—

Figure 1 is a view in elevation illustrating my 25 improved adjustable stretcher;

Fig. 2 is a broken edge view looking at the 30 right of Fig. 1;

Fig. 3 is a view in longitudinal section on the 35 line 3—3 of Fig. 1 and in this view a garment is shown in full lines on the stretcher;

Fig. 4 is an enlarged fragmentary detail view in 40 section on the line 4—4 of Fig. 1.

The particular stretcher illustrated comprises 45 a frame consisting of longitudinal bars 1, 1, connected by an upper transverse bar 2 and a lower transverse bar 3. The bars 1, 1 are preferably of wood and the bars 2 and 3 are preferably of metal, although it is to be understood that the invention is not limited to the particular materials employed.

The bars 1, 1 at their upper ends are bifurcated 50 to receive the bar 2 therein, and this bar 2 is connected to the bars 1, 1 by bolts 4 and wing nuts 5 clamping the bars together. The bar 2 is formed in at least one end with a longitudinal slot 6 through which the bolt 4 projects so that the desired adjustment of the bars relative to 55 each other can be made. The bars 1, 1 at their lower portions are formed with longitudinal slots 7 through which the bar 3 projects, and is likewise secured to said bars by bolts 4 and wing nuts 5. The bar 3 in at least one end is formed 60 with a longitudinal slot 8 receiving the bolt 4

so as to permit of the necessary adjustment between the bars. Furthermore, the bars 1, 1 are provided with a longitudinal series of openings or perforations 8' to receive in any of them the said bolts.

On the outer edges of the bars 1, 1, I locate 5 shaping strips 9 which are preferably of wood and are of semi-circular form in cross section as illustrated clearly in Fig. 4 of the drawing, and are of sufficient flexibility to permit of the necessary bending of the strips. These strips 9 are fixedly secured at one end to the bars 1 by screws 10 and at their other ends are provided with longitudinal slots 11 which are movable on headed 10 screws 12 fixed to the bars 1, 1, and also said slots 15 11 permit of the positioning of the lower bar 3 through the strips. The strips 9 are adjustably connected to the bars 1, 1, intermediate their ends, by any desired number of adjusting devices 12, which in the specific form illustrated, comprise 20 screws which move freely through openings 13 in the bars 1, 1 and are fixedly connected at their outer ends to the strips 9. I have illustrated the connection between the screws and the strips as constituting a threaded socket 14 in the strip 25 receiving the end of the screw, but it is, of course, to be understood that the screws may be operatively connected to the strips in any desired manner. On these screws 12 at opposite sides of the bars 1, 1, nuts 15 are located so that these nuts 30 may be moved freely on the screws to permit the strips to be given the shape desired and then clamped home against opposite sides of the bars 1, 1 to prevent further movement. While in the particular instance illustrated in Fig. 1, these 35 strips are shown as having a general convex curvature throughout their length, it is obvious that by adjusting the nuts 15 on the screws 12, the strips may be given a compound curvature or any other shape desired so as to properly shape 40 the particular garment supported thereon.

It will be noted, particularly by reference to Figs. 1 and 3 of the drawing, that the openings 45 13 above referred to constitute elongated slots in the bars 1 and the outer edges of these bars adjacent the slots are recessed. This arrangement not only permits the screws an adjustment longitudinally of the bars 1, but also permits of various angular dispositions of said screws to accommodate themselves to the varying shapes imparted 50 to the flexible strips 9.

As a holding means for the garment on the stretcher, I preferably employ what constitute ordinary clothespins 16 which carry spring tongues or clips 17 engaging over the bars 2 and 3, 55

and clamping the edges of the garment as illustrated at 18 in Fig. 3 of the drawing. These clothespins are alternately positioned on opposite sides of the bars 2 and 3, and I may employ as 5 many of these clothespins or garment clamping means as may be desired and they are freely removable and replaceable on the bars 2 and 3.

While I have illustrated and described what I believe to be a preferred embodiment of my invention, it is obvious that various slight changes may be made with regard to the form and arrangement of parts without departing from my invention, and hence I do not limit myself to the 10 precise details set forth but consider myself at 15 liberty to make such changes and alterations as fairly fall within the spirit and scope of the claims.

I claim:

1. In a stretcher, the combination of a frame 20 consisting of longitudinal and transverse bars operatively connected, strips located at the outer edge of the longitudinal bars and so connected thereto as to permit movement and bending of the strips relative to the bars, and adjusting 25 means intermediate the ends of the strips and the bars connecting said strips and bars and

capable of adjustment to vary the shape of the strips, said adjusting means comprising screws secured at their outer ends to the strips and projecting through bars of the frame and nuts on the screws at opposite sides of the bars, said bars having longitudinal slots therein receiving the screws and permitting of movement of the screws longitudinally of the bars and permitting various angular dispositions of the screws to compensate for the varying shapes of the flexible 10 strips.

2. In a stretcher, the combination of a frame consisting of longitudinal and transverse bars operatively connected, strips located at the outer edges of the longitudinal bars, strip adjusting 15 devices connected at their outer ends to the strips, said bars having longitudinal slots therein receiving the said adjusting devices and permitting movement of the latter longitudinally of the bars as well as permitting an angular disposition 20 of said devices relative to the bars, and means on the adjusting devices engaging opposite sides of the bars and operatively connecting said devices to the bars.

WILLIAM H. JACOBUS. 25
